UNITED STATES PATENT OFFICE.

JAMES A. CREWES, OF INDIANAPOLIS, INDIANA.

DOOR OPENING AND CLOSING MECHANISM.

Application filed March 4, 1926. Serial No. 92,355.

My said invention relates to improvements in mechanism for automatically opening and closing garage doors as a vehicle passes into and out of the same and consists in various 5 improvements in the construction and arrangement of parts, whereby various advantages are secured in the operation of the doors, all as will hereinafter be more fully described and claimed.

10 Referring to the accompanying drawings which are made a part hereof and on which similar reference characters indicate similar parts,

15 Figure 1 is a rear elevation or view from the inside of folding garage doors, illustrating the application of my invention,

Figure 2 a top plan view, and

Figures 3, 4 and 5 are detailed views.

20 In the drawings reference character 10 indicates a pair of folding garage doors secured by hinges 11 to side frames 12 and each door comprises a pair of sections connected by hinges 13 and adapted to fold inwardly to open position. In order to provide means for automatically opening the 25 said doors as an automobile or other vehicle of considerable weight is about to enter the garage or other building and also to automatically close said doors when the automobile has passed out of the garage, I provide a pair of vertically mounted operating rods 14 and 15, secured to the side frame, one adjacent each door. The rod 14 is of 30 a greater length than the rod 15 for a purpose hereinafter more fully explained. Operating arms 16 are fixed on said operating rods in substantially horizontal positions, adjacent the upper ends of the doors and said arms are provided with bifurcated outer 35 extremities 17 curved forwardly and having rollers 18 disposed in Z-shaped slots 19 in brackets 20 secured to the section of the door which is pivoted to the door frame.

40 The operating rods 14 and 15, mounted in hangers or supports 43 are provided on their upper ends with levers 21 formed with oppositely extending arms of equal length and connections 22 are provided between the opposite ends of the levers, said connections comprising rods or cables crossed to cause the doors to operate simultaneously in a similar manner. A track 23 is mounted above each pair of doors on the door frame and forms a guide for each free section of the doors. A bracket 25 carrying a roller 24 at its end is secured to the center of each

free section of the door and is bent inwardly at an angle so that the roller 24 is spaced about three inches from the plane of the door thereby eliminating any binding or 60 friction when opening or closing the doors.

A manually operable handle 26 is fixed on the operating rod 14 adjacent its lower end in a position capable of being readily manually manipulated to open or close the 65 doors. When the handle 26 is swung inwardly the rods 14 and 15 will be rotated to swing the arms 16 inwardly and said arms will cause the rollers 18 to move along the slot 19 in the bracket 20 to unlock and open 70 the doors and lock them in the open position. The brackets 25 and rollers 24 supported thereby travelling outwardly toward the sides of the doors and maintaining the outer edges of the doors in substantially the plane 75 of the door frame to cause the sections of each door to pivot on its respective hinges and swing to one side clearing the door way.

When the doors are swung to open position the rollers 18 will enter the recesses at 80 ends of the slots 19 and hold the door against movement until such time as the rod 14 operated by lever 26 is swung in a reverse direction to close the doors. In the closed 85 position the rollers 18 will be housed in the recesses at the opposite end of the inclined slot 19 and the doors will be held in closed position, preventing them from being opened by unauthorized persons from the exterior. 90

95 In order to provide means for opening and closing the doors automatically I fix a bevelled gear 27 on the lower extremity of the operating rod 14, and a gear casing 28 is mounted on the door frame about said gear and supports a horizontally disposed shaft 29 having a pair of segmental gears 30 and 31 fixed thereon and spaced about 90° apart for engagement with the bevelled gear 27 for rotating it in a clock-wise direction for closing the doors and in a contra-clock-wise direction for opening the doors. The segmental gear 30 is provided with an axial extension 32 provided with teeth and forming a clutch member adapted for engagement with a co-operating clutch member 33 loosely mounted on the shaft 29, but held in engagement with clutch member 32 by means of a helical spring 34. A lever 35 is secured to said clutch member 33 and is adapted to be depressed for rotating the clutch member 30 and also for rotating the clutch member 31 through the medium of the 100 105 110

shaft 29. In order to prevent reverse rotation of the shaft 29 and gears 30 and 31 mounted thereon when the lever 35 is elevated, I fix a ratchet 36 on the extremity 5 of the shaft 29 and mount a pawl 37 in a position to engage said ratchet. A gravity operated pawl may be utilized, however, I preferably provide a pawl formed of spring metal to constantly press against said ratchet.

10 In order to depress the lever 35 I provide a treadle 38 adjacent the front of the garage and a treadle arm 39 is pivoted thereto and extends beneath the operating lever 15 35 and is pivotally supported at its inner end by means of a bracket 40, a rod 41 has one end connected to the lever 35 and has its opposite end connected to the treadle arm 39, so that when the treadle is depressed the rod 20 41 will depress the arm 35 and rotate the segmental gears for operating the doors. In order to maintain the treadle arm and treadle in elevated position I provide a spring 42 preferably capable of withstanding 25 a weight approximately 400 pounds, so that the doors can be operated from without only when sufficient weight, as for example a portion of the weight of a vehicle is supported thereon.

30 In the operation of my device the manually operable handle 26 will first be operated to open the doors, whereupon the vehicle passing out of the garage will pass over the treadle and depress the same, rotating 35 the segmental gears, but one depression of the lever will merely bring the segmental gear 31 into position to engage the bevelled gear 27 and as the second vehicle wheel passes over the treadle it will rotate the 40 bevel gear 27 to perform the closing operation. When the doors are closed and a vehicle is driven up in front of the garage, the front wheel as it passes over the treadle 45 38 will open the doors while the second wheel passing over said treadle will only cause the clutch to override. The doors may then be manually closed by operation of the handle 26.

50 It will be obvious to those skilled in the art that various changes may be made in my device without departing from the spirit of the invention and therefore, I do not limit myself to what is shown in the drawings and described in the specification, but only as indicated in the appended claims.

55 Having thus fully described my said invention, what I claim as new and desire to secure by Letters Patent is:

60 1. In combination a door frame, a door pivoted at each side of the frame, separate irreversible pin and slot operators for each door, manual and pedal driving means for one of said operators and connecting linkage between the two operators, substantially as set forth.

65 2. In combination a door frame, a door pivoted at one side to said frame, a bracket on said door adjacent its free edge and having a slot therein, an operating arm having one end disposed in the slot in the bracket, an operating rod supporting the opposite end of said operating rod a lever mounted on said operating rod adapted to be manipulated for opening and closing the door, said bracket having a recess at each end of the 70 slot for receiving the end of the operating arm and thereby holding the door in open or closed position, substantially as set forth.

75 3. In combination a door frame, a door pivoted at each side of the frame, an operating rod supported on each frame adjacent each door, a lever on each operating rod, connections between the opposite ends of said levers whereby when one lever is 80 operated, the other lever will be operated in an opposite direction, an operating arm mounted on each of said operating rods, a connection between the outer end of each operating arm and its respective door, and a manually operable handle mounted on one of said operating rods adapted to be manipulated to rotate the operating rod for opening and closing said doors, substantially as 85 set forth.

90 4. In combination a door frame, a door mounted in the door frame, an operating rod mounted on said door frame and having one end slidably secured to the door, a gear on the lower end of said operating rod, 100 a pair of segmental gears adjacent said bevelled gear and adapted to alternately engage the same for rotating it in reverse directions, a clutch associated with said segmental gears, a lever carried by said clutch 105 for rotating the segmental gears in a step by step manner, a link depending from said lever, a treadle arm connected to said link, and a treadle on said treadle arm whereby pressure upon the treadle will cause the 110 door to open and close, substantially as set forth.

115 5. In combination a door frame, a door mounted in said frame, an operating rod mounted on said door frame in substantial 115 parallel relation to the door, a door engaging arm mounted on said operating rod, and means for rotating said operating rod in opposite directions for opening and closing the door, said means comprising a gear on said operating rod, segmental gears associated with said first mentioned gear and means for rotating said segmental gears for rotating the associated gear and operating rod alternately in opposite directions, substantially as set forth.

120 6. The combination of a door frame, a door mounted in said frame, an operating arm connected to said door for opening and closing the same, a rod mounted on said 130 door frame in substantial parallel relation

to the door and supporting said operating arm, a gear on said operating rod, a shaft mounted transversely of the operating rod adjacent said gear, a pair of segmental gears on said shaft having the teeth of one spaced a slight distance about their axis from the teeth of the other whereby when said shaft is rotated one segmental gear will engage the gear and rotate it in one direction, while immediately thereafter the other segmental gear will engage said gear and rotate it in a reverse direction, substantially as set forth.

7. The combination of a door frame, a door mounted in said frame, an operating arm connected to said door for opening and closing the same, a rod mounted on said door frame in substantial parallel relation to the door and supporting said operating arm, a gear on said operating rod, a shaft mounted transversely of the operating rod adjacent said gear, a pair of segmental gears on said shaft having the teeth of one spaced about their axis from the teeth of the other whereby when said shaft is rotated one segmental gear will engage the gear and rotate it in one direction, while immediately thereafter the other segmental gear will engage said gear and rotate it in a reverse direction and whereupon a continued rotation of the shaft will permit the gear on the operating rod to remain idle until the shaft has been rotated sufficiently to bring the first mentioned segmental gear into engagement with said gear to again operate the same, substantially as set forth.

8. The combination of a door frame, a door mounted in said frame, an operating arm connected to said door for opening and closing the same, an operating rod mounted on said door frame in substantial parallel relation to the door and supporting said operating arm, a gear on said operating rod, a shaft mounted transversely of the operating rod adjacent said gear, a pair of segmental gears on said shaft at opposite sides of said gear and having teeth spaced a slight distance about their axis from the teeth of the other whereby when said shaft is rotated one segmental gear will engage said gear and rotate it in one direction while immediately thereafter the other segmental gear will engage said gear and rotate it in a reverse direction and whereupon a continued rotation of the shaft will permit the gear on the operating rod to remain idle until the shaft has been rotated sufficiently to bring the first mentioned segmental gear into engagement with said gear to again operate the same and means for operating said segmental gears in a step by step movement, substantially as set forth.

9. The combination of a door frame, a door mounted in said frame, an operating arm connected to said door for opening and

closing the same, an operating rod mounted on said door frame in substantially parallel relation to the door and supporting said operating arm, a gear on said operating rod, a shaft mounted transversely of the operating rod adjacent said gear, a pair of segmental gears on said shaft having the teeth of one spaced a slight distance about their supporting shaft from the teeth of the other whereby when said shaft is rotated one segmental gear will engage said gear and rotate it in one direction while immediately thereafter the other segmental gear will engage said gear and rotate it in a reverse direction and whereupon a continued rotation of the shaft will permit the gear on the operating rod to remain idle until the shaft has been rotated sufficiently to bring the first mentioned segmental gear into engagement with said gear to again operate the same, means for operating said segmental gears in a step by step movement, said means comprising a clutch mechanism, a lever associated therewith, a treadle, a treadle arm connected to said treadle, and a link connecting said lever and treadle arm, substantially as set forth.

10. The combination of a door frame, a folding door mounted at each side on said door frame, a track above each folding door, co-operating means adjacent the forward edge of each door for engagement with its respective track, an operating rod mounted on the door frame adjacent each door and in substantially parallel relation thereto, a lever mounted on the upper portion of each operating rod, and having oppositely extending arms, cross connections between the opposite arms of said levers, whereby when one operating rod is rotated the other operating rod will be correspondingly rotated in the opposite direction, an operating arm mounted on each of said operating rods and having its outer end connected to the adjacent door, and means for rotating one of said operating rods, whereby the doors may be simultaneously opened or closed, substantially as set forth.

11. The combination of a door frame, a folding door mounted at each side on the door frame, a track above each folding door, co-operating means adjacent the forward edge of each door for engagement with its respective track, an operating rod mounted on the door frame adjacent each door and in substantial parallel relation thereto, a lever mounted on the upper portion of each operating rod and having oppositely extending arms, cross connections between opposite arms of said levers, whereby when one operating rod is rotated the other operating rod will be correspondingly rotated in the opposite direction, an operating arm mounted on each of said operating rods and having its outer end connected to its respective

door, and means for rotating one of said operating rods whereby the doors may be simultaneously opened or closed, said means comprising a treadle and a connection between said treadle and one of said operating rods whereby when the treadle is depressed the operating rod will be rotated for open-

ing and closing the doors, substantially as set forth.

In witness whereof, I have hereunto set ¹⁰ my hand at Indianapolis, Indiana, this 1st day of March, A. D. nineteen hundred and twenty-six.

JAMES A. CREWES.
